UNITED STATES PATENT OFFICE

WILLIAM Q. PFAHLER, OF TOLEDO, OHIO.

TANK-OUTLET.

1,113,683.

Specification of Letters Patent. Patented Oct. 13, 1914.

Application filed January 8, 1914. Serial No. 811,108.

To all whom it may concern:

Be it known that I, WILLIAM Q. PFAHLER, a citizen of the United States, residing at Toledo, in the county of Lucas and State of Ohio, have invented a new and useful Tank-Outlet, of which the following is a specification:

This invention relates to improvements in plugs for tank outlets.

10 An object of the present invention is to provide an outlet device or plug which will allow the tank to be readily drained and at the same time will prevent foreign material from entering the outlet pipe.

15 A further object is to provide an outlet device with a storage chamber for the deposit of the sediment and foreign material which may be present in the liquid contents of the tank and thus it will be prevented 20 from entering the outlet pipe.

A further object is to provide a device of the above mentioned type which may be readily removed from the tank for the purpose of cleaning and to ascertain the condition thereof.

25 With the foregoing and other objects in view which will appear as the description proceeds, the invention resides in the combination and arrangement of parts and in 30 the details of construction hereinafter described and claimed, it being understood that changes in the precise embodiment of the invention herein disclosed, can be made within the scope of what is claimed, without departing from the spirit of the invention.

35 In the drawings accompanying this specification and forming a part thereof, the preferred embodiment of my invention is 40 illustrated, in which:—

Figure 1 is a view in elevation of my device taken through the longitudinal axis thereof and illustrating a portion of the tank to which it is secured. Fig. 2 is a sectional view taken on the line 2—2 of Fig. 1.

45 Referring now to the drawings in which similar reference numerals designate analogous elements throughout the several figures, 3 represents the side wall of a tank and 4 the bottom. The bottom 4 of the tank is provided with the outlet opening 5 extending therethrough and to the side walls of which is secured my improved device.

55 Secured to the bottom 4 of the tank by rivets 6 or other equivalent means, is the plug attaching member 7 which includes the

internally threaded sleeve 8 and the flange 9 carried thereby. The flange 9 has the rivets 6 extending therethrough whereby the said plug attaching member is rigidly secured to the tank and effects a liquid-tight juncture therewith.

The plug 10 which is detachably secured to the plug attaching member 8 includes a central pipe-like body portion 11 which is threaded at its lower extremity as at 12 and to which lower extremity may be secured a pipe for the conducting of the liquid which flows from the tank to any desired point. It is to be noted that the device herein disclosed is particularly adapted for use with gasoline tanks in which a pipe-like body portion 11 will communicate with the carbureter and thus it is of prime importance to prevent any foreign material from entering the pipe-like body portion as the same would eventually find its way to and lodge in the needle valve of the carbureter and prevent the proper and efficient working thereof.

Carried by, and in the present drawings illustrated as being formed integral with, the pipe-like body portion 11 is the outstanding disk 13 and which is provided with the concentric upstanding flanges 14 and 15. The outermost flange 15 is externally threaded and is spaced a slight distance from the extreme edge of the disk so as to threadedly engage the sleeve 8 and with the peripheral edge thereof lying flush with the outer surface of the sleeve. The outer flange 15 is of relatively less height than the inner flange 14 so that should for any reason sediment collect upon the top edge of the flange 15 it will not be liable to gravitate into the annular opening between the flange 14 and the body portion 11. Rigidly secured to the outer surface of the flange or sleeve 14 is the wire screen 16 which is dome-shaped as at 18 at its upper extremity and which is of sufficiently fine mesh to practically exclude all foreign material of such dimensions as would interfere with the proper working of the valves of a carbureter. The wire screen 16 is cylindrical in outline as illustrated in Fig. 2 and completely incloses and protects the opening 19 which extends through the pipe-like body portion 11. The space intermediate the flanges or sleeves 14 and 15 forms an outlying collecting receptacle 20 in which the foreign material will collect which is of too large dimensions to

pass through the screen 16. The space between and defined by the upstanding flange 14 and the body portion 11 forms a receptacle 21 in which is adapted to collect any fine particles which may pass through the screen 16. However, the collection of material within the receptacle 21 is a remote contingency as the screen is made sufficiently fine to exclude all articles from passing therethrough. In order that the material collected within the outlying and annular compartment 20 may be drained therefrom without requiring the removal of the entire plug, a pet cock 22 is provided communicating with the bottom of the receptacle and which may be opened either for the purpose of draining the sediment which may have become deposited within the said receptacle or for the draining of the entire contents of the tank as may be desired. The body portion 11 which includes the outlet central opening 19 is of sufficient length so as to extend above the bottom 4 of the tank so as to further prevent the passing of foreign material through the screen which might happen by the force of the current were the said body portion to terminate below the bottom 4 of the tank. The disk 13 is provided with the enlarged portion 23 which presents a wrench engageable surface and allows for the plug to be readily attached or detached from the supporting and plug attaching member 7. Thus when the plug is removed, the screen is removed therewith, which allows the same to be inspected and cleaned should it be found so necessary.

Having thus described my invention, what I claim is:—

1. A device of the class described comprising a plug attaching and supporting member including a sleeve, means for rigidly securing the same to and extending below the

side walls of a tank opening, a plug detachably secured to the said sleeve and including a centrally extending pipe-like body portion, an outstanding disk carried by said body portion intermediate its ends, the said disk provided with two concentric upstanding sleeves, the outermost sleeve being detachably secured to the said plug attaching and supporting member sleeve, the said pipe body portion extending above the plug attaching member when secured thereto, the annular space between the said upstanding sleeves of the disk forming a dirt collecting receptacle, a cylindrical screen carried by and affixed to the innermost disk sleeve and extending above and encompassing the said pipe body portion, and means communicating with the said dirt receiving receptacle adapted to drain the same.

2. A device of the class described comprising a sleeve, means for securing the same to the bottom of a tank, a pipe provided with a disk intermediate its ends, the said disk engaging the said sleeve with the pipe extending above the bottom wall of the tank, said disk provided with a concentric upstanding flange, a wire screen carried by said flange spaced from the upstanding portion of the pipe and housing the same therein, the annular space between the screen and the said sleeve forming a dirt collecting receptacle, the annular space intermediate the pipe and the said annular flange defining a second foreign material collecting receptacle.

In testimony that I claim the foregoing as my own, I have hereto affixed my signature in the presence of two witnesses.

WILLIAM Q. PFAHLER.
